UNITED STATES PATENT OFFICE.

JUDSON M. BLAKE, OF CHICAGO HEIGHTS, ILLINOIS, ASSIGNOR TO AMERICAN MAN-
GANANE STEEL COMPANY, OF CHICAGO, ILLINOIS, A CORPORATION OF MAINE.

LOWER DISK FOR ROTARY CRUSHERS.

Application filed January 29, 1921. Serial No. 440,846.

To all whom it may concern:

Be it known that I, JUDSON M. BLAKE, a citizen of the United States, residing at Chicago Heights, in the county of Cook and State of Illinois, have invented certain new and useful Improvements in Lower Disks for Rotary Crushers, of which the following is a specification.

My invention relates to rotary crushers and particularly to a lower plate or disk for rotary crushers. It is designed primarily for use in crushers of the Symons type, in which there is a gyratory and oscillatory movement of one disk relatively to the other disk, but it is applicable also to disk crushers operating by mere relative rotation between the disks.

For the fine reduction of ore and the like, the Symons type of crusher employs two horizontally disposed disks, of which the lower one is substantially flat and the upper one has a conical central portion into which the ore is fed, surrounded by a marginal flange substantially parallel with the lower disk and coacting therewith to crush the material. For fine reduction the minimum opening between the upper and lower crushing faces of a machine of the kind referred to will be about $\frac{1}{16}$ of an inch, and substantially all the crushing of the ore and the principal wear upon the disks take place near the peripheries of the parallel faces of the disks and over an area extending inwardly therefrom approximately 6 inches. As crushing continues, the worn surfaces of the disks recede, and this necessitates adjustment to maintain the opening of $\frac{1}{16}$ of an inch between the crushing areas. After continued service the wear is so great that a shoulder or "bell" is formed on the upper surface of the lower disk, which comes so close to the upper disk as to prevent the feed of ore from the central space provided by the cone of the upper disk to the marginal grinding surfaces. When this condition has been reached, replacement of the lower disk has heretofore been necessary for fine crushing.

Again, in the Symons type of crusher, it has been proposed to merge the parallel crushing face of the upper disk with the conical face thereof through the medium of an intermediate annular crushing area (so called) and to curve said area in a radial

axial plane of the disk so that, in coaction with the flat under disk, it will crush the material and prepare it for admission to the fine reduction area between the parallel faces. But this curved area soon reduces and eventually disappears under wear of the upper crushing surface.

My invention is directed to a lower disk so formed as to prevent the formation of the "bell" or shoulder adjacent the upper disk which prevents feed of ore to the crushing surfaces of the disks, and at the same time to render unnecessary the intermediate curved annular area, and permit the conical and flat surfaces to be merged abruptly.

In carrying out my invention, I form in the portion of the upper surface of the lower disk, over an area inside of the straight or parallel crushing area, a feeding recess or concavity that merges with the straight crushing area in an annulus that is radially beyond the annulus of the shoulder formed by the merger between the conical and straight surfaces of the upper disk. This recess or concavity is thereby adapted to serve the purpose of passing the material beneath said shoulder. I also extend the concavity or recess outward beyond the annular locus of the shoulder or "bell" that develops from the coaction of a Symons upper disk with a continuously flat lower disk, and thereby maintain an unobstructed feed from the inner recess of the lower disk to the outer crushing face thereof as the latter face wears away.

The various novel features of my invention will be apparent from the following description and drawings and will be particularly pointed out in the appended claims.

In the accompanying drawings:

Figure 1 shows a vertical sectional view of a lower disk constructed in accordance with my invention and a portion of an upper disk; and

Figure 2 is a top plan view of the lower disk of Figure 1.

The upper disk B is formed with a flat marginal portion 5 extending outwardly from the conical portion 5^a. The lower disk A is provided with a flat marginal portion 6, and the usual central shaft opening 7. Formed in the upper surface of the lower disk A is an outwardly tapering an-

nular recess or depression 8, the outer margin 9 of which is arranged outwardly beyond the shoulder 10 formed on the upper disk, by the merger of the inner face of the conical portion 5^a and the lower surface of the straight marginal portion 5 thereof. The inner margin 11 of the recess 8 rises to a higher level than the recess and terminates short of the shoulder 12 surrounding the central opening 7 in the disk. The depth of the depression 8 is made to suit the condition of service, such as size and speed of the mill and class and quality of ore to be crushed. In service the upwardly presented annular grinding surface 13 of the lower disk A may wear a distance equal to the depth of the pocket 8, or until the surface 13 is flush with the bottom of the recess 8, before any barrier to the feed will develop. The ore which is fed through the usual hopper into the conical portion of the upper disk B rests on the lower disk A and is driven outwardly by centrifugal action between the marginal portions of the disks where the ore is crushed or to within reach of the overhanging portion 10 which assists in rolling the pieces into the crushing space. The crushing opening may be varied to suit conditions. The recess 8 merges very gradually with the surface 13, and will be worn down to some extent and its obliteration delayed by the grinding effect of the overhang 10. Continued use of the lower disk will increase the wear on the surface 13 thereof and gradually this surface will be worn below the bottom of the recess 8, however, the depth of the recess 8 is such as to prevent the formation of a "bell" beneath the shoulder 10 in disk B that would prevent the discharge of ore to the marginal portions of the disks. Wear of the lower disk may continue until the marginal portions are so thin as to call for replacement.

By forming an annular depression in the upper surface of the lower disk with the outer periphery of the depression starting a slight distance beyond the juncture of the conical wall of the upper disk with the lower, flat surface thereof, and with the inner periphery near the central portion of the disk, or surrounding the usual central opening therethrough. An ore bed is maintained that forms the surface over which the material travels to the grinding faces and greatly relieves the lower disk from friction. With this construction it is possible to prolong the life of the lower disk considerably as the depth of the pocket or recess is made proportional to the thickness of the disk so that as the marginal portion of the disk becomes worn a shoulder or "bell" will not be formed on the lower disk of sufficient height to stop the flow of the ore until such time that the disk is worn so thin as to be discarded.

By way of example let it be assumed that the lower disk is 48 inches in diameter and about 2 inches in thickness, with a flat disk of this size the "bell" or shoulder would start to form after the marginal portion of the lower disk had worn about $\frac{1}{8}$ of an inch and this shoulder or "bell" would extend around on the lower disk in contact with the shoulder on the upper disk so that the shoulder on the lower disk would be from a quarter of an inch to $\frac{1}{8}$ of an inch higher than the worn portion of the lower disk. When the lower disk has been worn from 1 to $1\frac{1}{8}$ inches the "bell" would be so high as to preclude the passage of ore to the grinding portions of the disks and necessitate replacement of the lower disk. With the lower disk constructed in accordance with my invention 48 inches in diameter and 2 inches thick the recess or pocket would be formed about $\frac{3}{8}$ to $\frac{1}{2}$ of an inch deep starting at about 6 inches from the outside edge of the disk and terminating near the central shaft opening in the disk. Consequently with the marginal or grinding portions of the lower disk worn about $\frac{3}{8}$ of an inch the surface of the disk will be perfectly flat. With the marginal portion worn $\frac{1}{2}$ of an inch a "bell" will be formed of only $\frac{1}{2}$ of an inch and when the plate has worn to 1 inch or $1\frac{1}{8}$ inches the "bell" will be only $\frac{1}{8}$ to $\frac{1}{16}$ of an inch high, which will not prevent the passage of ore to the grinding portions of the disk. Before the "bell" is deep enough to interfere with the passage of the ore the grinding portions of the lower disk may be worn another $\frac{3}{8}$ of an inch or about $1\frac{1}{2}$ inches total wear before the "bell" will interfere with the passage of ore to the grinding portions. It will thus be seen that the full effectiveness of the lower disk is attained as the disk when worn to only half an inch in thickness is ready to be replaced by a new one.

While I have described more or less precisely the details of construction of my invention, I do not wish to be understood as limiting myself thereto, as I contemplate changes in form and the proportion of parts and substitution of equivalents as circumstances may suggest or render expedient, without departing from the spirit of my invention.

I claim:

1. A disk crusher comprising upper and lower disks constructed with substantially horizontal opposed peripheral crushing faces; the upper disk having a feeding cavity that develops a shoulder at the inner margin of its said peripheral crushing face; and the lower disk being constructed with an upwardly presented annular recess that extends radially outward beyond said shoulder.

2. A disk crusher comprising upper and

lower disks constructed with substantially horizontal opposed peripheral crushing faces; the upper disk having a feeding concavity that develops a shoulder at the inner 5 margin of its said peripheral crushing face; and the lower disk being constructed with an upwardly presented annular recess that extends radially outward beyond said shoulder and tapers upwardly to the level of the peripheral crushing face of said lower 10 disk.

Signed at Chicago Heights, Ill., this 20th day of January, 1921.

JUDSON M. BLAKE.
